[57] **CLAIM**

The ornamental design for a detachable ornament for footwear, as shown and described.

DESCRIPTION

FIG. 1 is a front elevational view of a detachable ornament for footwear embodying my new design.

FIG. 2 is a side elevational view taken from the right hand side of FIG. 1.

FIG. 3 is a rear elevational view thereof.

FIG. 4 is a side elevational view taken from the left hand side of FIG. 1.

FIG. 5 is a front elevational view of a detachable ornament for footwear showing a second embodiment of my new design.

FIG. 6 is a front elevational view of a detachable ornament for footwear showing a third embodiment of my new design.

FIG. 7 is a side elevational view taken from the right hand side of FIG. 5.

FIG. 8 is a side elevational view taken from the right hand side of FIG. 6.

FIG.1

FIG.2

FIG. 3
